STOVE HANDLE

Alva R. Jain and Frank Merrell Spence, Galveston, Ind., assignors to Globe American Corporation, Kokomo, Ind., a corporation

Application July 7, 1951, Serial No. 235,642

2 Claims. (Cl. 16—111)

1
This invention relates to a stove handle and particularly a bar handle to be applied to a door for a stove compartment, such as the oven or broiler.

It is the purpose of this invention to provide an elongated bar handle and the mounting brackets therefor all of stamped sheet metal, and wherein the bar handle gives the appearance of a solid cylindrical metal bar.

More particularly, the invention resides in the structure formed of sheet metal and assembled which enables a bar handle of this character, including its mounting brackets, to be produced in a more economical and facile manner than heretofore.

The invention is accomplished, in general, by rolling an elongated sheet metal piece about its edges to form an arcuate cross section with rolled in groove forming inner edges, forming a pair of bracket members of stamped sheet metal adapted to slide or telescope into the bar from each end in an interlocking relation with the inturned edges, each of said brackets being formed with a bent up end to about the open ends of the formed bar and simulate a solid bar construction.

The full nature of the invention will be understood from the accompanying drawings and the following description and claims:

Fig. 1 is a front elevation of a stove illustrating the mounting of the handle thereon,

Fig. 2 is a rear elevation of the bar handle showing one of the brackets telescoping at the left end thereof with a portion of the bar broken away, and the pre-formed bracket and end closure separated therefrom in position to be telescoped into the opposite end thereof.

Fig. 3 is an enlarged section taken on the line 3—3 of Fig. 1 with a portion thereof broken away.

As illustrative of the invention there is shown in the drawings a gas range 10 having the usual back panel 11 extending upwardly from the cooking surface 12. Below the cooking surface the stove is provided with one or more compartments which may include an oven, a broiler, and perhaps a utensil compartment. As shown in Fig. 1 there are three of such compartments, each having a hinged door 13, 14 and 15, respectively. Secured on each door there is provided an elongated bar handle 16 for grasping to open and close the door in the usual manner. The bar handle 16 is formed of sheet metal having an exposed curved surface indicated at 17, terminating in rolled in edges 18 to give the illusion from the front of the stove of a solid bar of metal. The rolled in edges provide locking grooves 19 open at opposite

ends of the bar for telescopically receiving therein the mounting brackets in the manner illustrated in Figs. 2 and 3.

There is provided such a mounting bracket to be telescopically received at opposite ends of the bar, each of the said brackets, together with the corresponding end closure, being formed of stamped sheet metal. One of the bracket closures is shown at the right hand end of Fig. 2 before being slidably received in the open end of the bar, and comprises a base plate 20 curved transversely thereof to conform and mate with the inner curved surface of the bar. Stamped from one end of the base plate 20 there is formed an enclosure cap 21 which is slightly dished and of an oval shape, likewise conforming to the cross sectional curvature of the bar, including a continuation of the surface 17. Said cap is bent upwardly at right angles to the base plate so that when the base plate is telescoped into the bar, the cap will fit snugly in the open end of the bar and give the illusion of the end of a solid bar.

Secured to the base plate 20 by spot welding there is an outwardly extending bracket 22 of inverted U-shaped cross section with inwardly bent outer wing portions 23 each of which is formed with a central recess so that when in their inwardly bent position their mating recesses will form an opening indicated at 24 to receive a stove bolt 25 for securing said bracket directly to the outer surface of the compartment door 13, as shown in Fig. 3.

The bracket 22 is secured by welding or the like to its base plate 20 through the medium of a pair of inwardly-extending wing mountings 23a lying across the inner end of the bracket in abutting relation for mounting support of the bracket on the base plate.

After the bar 16 is formed with the desired cross sectional curvature and the rolled in edges, the pre-formed mounting units, including the base plate 20, bracket 22 and end closure cap 21, is telescoped into the opposite ends of the bar, respectively, so that the base plate firmly interlocks with the locking grooves 19 formed by the rolled in edges 18, and with the end closure cap seating snugly into abutting relation with the open ends of the bar. With this assembly the sheet metal bar and mounting brackets may be readily secured to the compartment door in such relative position on the stove as to give the visual appearance of a solid bar handle.

The invention claimed is:

1. A stove handle for mounting on a compartment door of a stove comprising an elongated

sheet metal bar curved in cross section to provide rearwardly and inwardly extending rolled-in edges to provide opposed elongated locking grooves, a pair of sheet metal units for mounting said bar on the door, each of said units including a sheet metal base plate conforming to said curvature of the bar and interlocking with said locking grooves, one end of said base plate extending laterally therefrom adjacent the end of said bar to provide an end closure cap therefor, a bracket secured to each base plate to extend outwardly therefrom formed of sheet metal of inverted U-shape in cross section terminating in inwardly extending wing portions to provide end members therefor, one of said end members being rigidly secured to said base plate and the other end member being formed with an aperture therein for receiving a stove bolt for locking it in abutting relation against the surface of the door with said bar extending transversely of the door in spaced relation thereto for hand gripping.

2. A stove handle for mounting on a compartment door of a stove comprising an elongated sheet metal bar curved in cross section to provide rearwardly and inwardly extending rolled-in edges to provide opposed elongated locking grooves, a pair of sheet metal units for mounting said bar on the door, each of said units including a sheet metal base plate conforming to the

inner curvature and of a dimension to fit snugly within the inner surface of said bar for telescopically sliding into the opposite open ends of said bar with the opposed edges embraced and interlocked by said locking grooves, one end of each plate having an end closure cap extending laterally therefrom with edges curved to conform with the rolled-in edges of said bar and provide an end closure therefor, a supporting bracket secured to and extending outwardly from the base plate of each said unit having an aperture formed therein, and a locking bolt extending through said aperture for securing the ends of the respective brackets in abutting relation against the surface of the door with said bar extending transversely of the door in spaced relation thereto for hand gripping.
